(57) **CLAIM**

The ornamental design for a battery pack, as shown and described.

DESCRIPTION

FIG. 1 is a perspective view of a battery pack showing my new design;

FIG. 2 is another perspective view of the battery pack of FIG. 1;

FIG. 3 is a right side view of the battery pack of FIG. 1;

FIG. 4 is a left side view of the battery pack of FIG. 1;

FIG. 5 is a rear view of the battery pack of FIG. 1;

FIG. 6 is a front view of the battery pack of FIG. 1;

FIG. 7 is a top view of the battery pack of FIG. 1;

FIG. 8 is a bottom view of the battery pack of FIG. 1;

FIG. 9 is a perspective view of another embodiment of a battery pack;

FIG. 10 is a right side view of the battery pack of FIG. 9;

FIG. 11 is a left side view of the battery pack of FIG. 9;

FIG. 12 is a rear view of the battery pack of FIG. 9;

FIG. 13 is a front view of the battery pack of FIG. 9;

FIG. 14 is a top view of the battery pack of FIG. 9; and,

FIG. 15 is a bottom view of the battery pack of FIG. 9.

In the drawings, the evenly-spaced broken lines represent portions of the article which form no part of the claimed design. The dash-dot broken lines represent a boundary to the claimed design and form no part thereof.
